(57) **CLAIM**

The ornamental design for a waist hanging fan as shown and described.

DESCRIPTION

FIG. 1 is a perspective view of a waist hanging fan showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area 9 shown in FIG. 1.

The broken lines depict portions of the waist hanging fan that form no part of the claimed design. The dot-dash broken lines in FIGS. 1 and 9 depict the boundaries of the detail enlargements that form no part of the claimed design.
